[57] CLAIM

The ornamental design for a removable drive cover having flush surface, as shown and described.

DESCRIPTION

FIG. 1 is a perspective view of a removable drive cover having flush surface showing my new design;

FIG. 2 is a front elevational view thereof;

FIG. 3 is a top plan view thereof;

FIG. 4 is a right side elevational view, the left side elevational view being a mirror image; and,

FIG. 5 is a bottom plan view thereof.

The broken line drawing in FIG. 1 is for illustrative purposes only and forms no part of the claimed design.
